[57] **CLAIM**

The ornamental design for a combined valve housing and escutcheon, as shown.

DESCRIPTION

FIG. 1 is a perspective view of a combined valve housing and escutcheon showing my new design;

FIG. 2 is a front elevational view thereof;

FIG. 3 is a right side elevational view thereof, the left side being the mirror image thereof;

FIG. 4 is a top plan view thereof;

FIG. 5 is a bottom plan view thereof;

FIG. 6 is a rear elevational view thereof;

FIG. 7 is a perspective view of a second embodiment of the combined valve housing and escutcheon shown in FIG. 1;

FIG. 8 is a front elevational view thereof;

FIG. 9 is a right side elevational view thereof, the left side being the mirror image thereof;

FIG. 10 is a top plan view thereof;

FIG. 11 is a bottom plan view thereof; and

FIG. 12 is a rear elevational view thereof.
